UNITED STATES PATENT OFFICE.

HERMANN FRIEDRICH WILHELM LUCKE, OF ALTONA-ON-THE-ELBE, GERMANY.

DEVICE FOR REDUCING THE PITCHING OF SHIPS.

Application filed November 9, 1926, Serial No. 147,211, and in Germany July 29, 1926.

This invention relates to a device for reducing the pitching of ships and has for its object to reduce pitching, especially in the case of ships travelling under ballast, in such a manner that the annoying movement of the propeller out of the water is eliminated during pitching and an idle running of the propeller is obviated.

Endeavours have been made to overcome this drawback by various means but as the means employed were mostly too complicated or did not fulfill their purpose, they were abandoned.

For example rotary plates have been arranged outside the hull of the ship, these plates being adapted to be brought into their operative position by an extremely complicated device.

According to the present invention guide members are arranged on both sides of the rear stem of the vessel, these members extending close up to the propeller blades. In order to enable a balance of the suction action above and below the guide members to be obtained more easily, the guide members are provided with openings located near the hull of the ship. For the purpose of removing the load of surface pressure further openings of suitable shape are provided.

In the accompanying drawing are illustrated two examples of construction of the subject of the invention.

Figure 1 is an elevation of the rear stem of a ship with a guide member consisting of a plate.

Figure 2 is an elevation of the rear stem with a guide body composed of a number of plates fitted together in the form of a hollow body.

Figure 3 is a plan of the rear stem.

Figure 4 is a plan of a guide member consisting of a plate.

Figure 5 is a view of the interior of a guide member composed of a number of plates, and

Figure 6 is a section on the line A—B of Figure 5.

At the rear stem of the ship stationary guide members *a* are provided on each side thereof. The guide members may be composed of single plates or of a number of plates in which latter case the plates are fitted together so as to form a hollow body. The guide members *a* are of such a shape that they extend as close as possible to the propeller blades *b*. In order to obtain a satisfactory balance of the suction above and below the guide members *a* these latter are provided with openings *c* which are arranged near the hull of the ship. In order to remove the load of surface pressure the guide members are also provided with openings *d*.

By providing such guide members the pitching of the ship, even when travelling under ballast, is considerably reduced as the guide members oppose a considerable resistance to pitching.

Having thus described my invention what I claim as new and desire to secure by Letters Patent is:—

A device for reducing the pitching of ships, wherein stationary guide members are provided on both sides of the rear of the ship and extend close up to the propeller blades and wherein the guide members consist each of a number of plates which are formed into a hollow body.

In testimony whereof I have affixed my signature.

HERMANN FRIEDRICH WILHELM LUCKE.
